UNITED STATES PATENT OFFICE.

EDWARD ROBERTS, OF ISHPEMING, MICHIGAN.

MAIL-BAG CATCHER AND DELIVERER.

No. 877,800.

Specification of Letters Patent.

Patented Jan. 28, 1908.

Application filed October 25, 1907. Serial No. 399,084.

To all whom it may concern:

Be it known that I, EDWARD ROBERTS, a subject of the King of Great Britain, and a resident of Ishpeming, in the county of Marquette and State of Michigan, have invented 5 certain new and useful Improvements in Mail-Bag Catchers and Deliverers, of which the following is a specification.

My invention is an improvement in apparatus 10 for handling mail bags; and consists in certain novel constructions and combinations of parts as will be hereinafter described and claimed.

In the drawings Figure 1 is a perspective 15 view of the invention as in use. Fig. 2 is a detail face view partly in section of the crane for use on the cars. Fig. 3 is a detail vertical section on about line 3—3 of Fig. 2. Fig. 4 is a similar section showing the parts 20 in a different position from that shown in Fig. 3. Fig. 5 is a detail top plan view of a portion of the crane. Fig. 6 is a detail top plan view illustrating the reversibility of the double armed bag catcher, and Fig. 7 is a 25 detail view illustrating said bag catcher, parts being shown in section.

In carrying out the invention, I employ a crane A for application to a car, and a catcher to be supported alongside the track. 30 The crane A, of which I may employ two, one at each side of the doorway C, as shown in full and dotted lines Fig. 1, is pivoted at A' at one end to the car so it may be turned out to the full line position shown in Fig. 1 35 for use, or into the dotted line position shown in the same figure when not in use, and when turned out for use the crane rests against the wall of the doorway and may be secured by a turn button D, pivoted to the car so it may 40 be turned to the full line position shown in Fig. 1 to hold the crane in position for use or may be turned down, as indicated in dotted lines in Fig. 1 to release the crane and permit the same to be adjusted to the dotted line 45 position shown in the same figure. This crane therefore may be swung between this position for use and the other position and in its other or dotted position will be housed entirely within the car so it will not be a 50 source of danger and when turned to position for use will be securely held in such position by the turn button shown in Fig. 1, before described. Near its outer end the crane A is provided with means for holding

and releasing the bag carrying ring E. This 55 ring is of sufficient size and strength to support a number of bags and in practice any desired number of bags is attached to the ring, as will be understood from Fig. 1 and the ring is of sufficient size to receive and 60 permit the operation within it of the head or abutting portion F' of the latch F, which latch operates to hold the retaining portion G in position to secure the ring E in the 65 operation of the invention as presently described.

The crane A forms a support for the ring holding and securing devices and is provided on its rear side with a central pin H on which the ring is suspended and with side pins H' 70 which are arranged above the ring and limit the upward and swinging movement thereof. These pins H and H' project rearwardly from the crane and the ring is simply slipped over the pin H from the rear so that it will 75 readily drop from the pin H when the retaining device presently described, is released by the freeing of the latch F. This retaining device G is pivoted at G' and bears in the position of parts shown in Figs. 1, 2 80 and 3 against the upper portion of the ring E and holds said ring on the pin H. If now the plate G be released it may be swung to the position shown in Fig. 4 and thus release the ring with the attached bags so the latter 85 may be held by the catcher. The retaining plate G is provided at its upper end with the forwardly projecting arm or lug G², which engages in the position of parts shown in Fig. 3 with the corresponding lug F² on the 90 upper end of the latch F. I thus provide the retaining plate and the latch with interengaging parts so that the latch when adjusted to normal position will hold the retaining plate in position to secure the ring 95 in connection with the crane, as will be understood from Figs. 2 and 3 of the drawing. At its lower end below its pivot F³ the latch has a head F' for engagement by the bag catching device, as will be understood from Figs. 100 1 and 3, so that the bag catching device releases the ring and also catches said ring in order to support the bags carried thereby. It will be noticed, especially from Figs. 1 and 3, that the head F' is inclined or deflected rearwardly, the inclined surface affording a glancing blow for the hook I² of the catcher and also setting the said head 105

nearer to the ring C suspended on the pin H, as best shown in Fig. 3. Manifestly the head F' may be of any suitable size and the ring E may be of any suitable size and strength and the parts may be made of any suitable material and may be conveniently supported to operate in the manner and for the purpose before described.

The bag catching device comprises a double armed yoke I whose arms I' curve toward their extremities and are provided at such points with upturned hooks I², and the yoke I is provided at its middle with a depending shaft I³ journaled vertically in a tubular upright J, so it can be turned between the positions shown in full and dotted lines Fig. 6. The shaft I³ and upright J are provided with coincident openings I⁴ and J⁴ through which a pin K may be passed to secure the catcher in the position shown in full lines in the same figure. By this means the catcher may be set to receive bags from trains going in one direction or the other as may be necessary in the practical operation of the invention. It will be noticed in this connection that the pin K can be conveniently removed to permit the adjustment of the catching device and then inserted to hold the same in any desired position.

30 The upright J may be steadied in position by the strut braces J', see Fig. 1, and is designed in practical use to be supported at stations or depots where it is desired to deliver the bags.

35 In operation it will be noticed the bags are secured to the ring E in any suitable manner and any desired number of bags may be so secured and the ring may be applied to the crane when the latter is within the car and 40 the latter is moving rapidly toward the point where it may be desired to deliver the bags. The crane may then be swung to the position shown in Fig. 1 and secured by the latch or fastening D and the head or abutment F' 45 within the ring will be in position to strike the arm I' of the catcher nearest the car. As the car approaches the catcher the hook I² of the catcher will strike the head F', throw the latch to position shown in Fig. 4, and thus release the retaining plate G so the 50 ring will drop upon the catcher arm I' and will be prevented by the hook I² from slipping off said arm. Manifestly the arms I' may be of any suitable length found necessary or desirable in securing the bags and it will be understood that the invention will be found especially useful in delivering a 55 number of bags from express trains at points where it may be desired to subsequently deliver such bags to accommodation trains along the road.

It will be noticed the construction is simple, and can be inexpensively made and 60 applied to a car now in use as well as those

in the course of construction, and it is strong and durable and will efficiently operate for the desired purpose.

I claim—

1. The combination in an apparatus for 70 handling mail bags, of a crane pivoted at one end to the car, a latch for securing the crane in position for use, a ring supporting pin at the rear side of the crane, pins on the crane to overlie a ring held on the supporting pin, a swinging retaining plate for securing the ring on the supporting pin the said plate being provided at its upper end with a forwardly projecting arm or portion, a latch pivoted between its ends to the crane 75 and having at its upper end a rearwardly projecting arm engaging with that of the retaining plate and provided at its lower end with a head or abutment portion for engagement by a catcher device whereby said device may 80 operate to free the latch from the retaining plate, and a bag catcher comprising a double armed yoke having its arms provided with upturned hooks and provided at its middle with a depending shaft and an upright in 85 which said shaft is mounted to turn whereby the catcher may be adjusted to receive bags from trains moving in either direction, substantially as set forth.

2. The combination in an apparatus for 95 handling mail bags, of a car crane having a ring support, a retaining device for holding the ring on said support and a latch for securing the retaining device in position to hold the ring and having a projecting head or 100 abutment portion below the ring support for engagement by the catching device, substantially as set forth.

3. In apparatus substantially as described a crane, a ring support on one side of the 105 crane, a ring retaining device on the other side of the crane for holding the ring on its support, and a latch on the opposite side of the crane from the retaining device and having means interengaging with the said device 110 for holding the same in position to secure a ring upon its support, said latch having a portion for engagement by a bag catching device, substantially as set forth.

4. The combination with a car of a swing- 115 ing crane pivoted thereto and having a ring supporting pin, a retaining plate pivoted to the crane and movable to position to secure a ring upon said pin, and a latch pivoted to the crane and interengaging with the retaining plate whereby it may secure the latter in position to hold the ring on the pin and to free said plate to release the ring, substantially as set forth.

5. The combination with a crane, of a pin 125 or projection thereon for supporting a ring, and projections on opposite sides of said supporting pin to overlie a ring held thereon whereby to prevent any displacement of the ring, a retaining device for holding the ring 130

on its supporting pin, and a latch for securing and releasing said retaining device, substantially as set forth.

6. In an apparatus substantially as described a double armed bag catcher pivoted vertically at its middle whereby it may be adjusted to set one of its arms toward a track and facing in one direction or its other arm toward such track and facing in the opposite direction to adapt it to receive bags from trains moving in one or the other direction and a bag supporting ring to be received by said arms and movable along the latter, substantially as set forth.
- 15 7. In an apparatus substantially as described a double armed bag catcher provided between its ends with a depending shaft and a tubular upright receiving said shaft whereby the catcher may be adjusted to set one or 20 the other of its arms to position to receive the bag and a bag supporting ring to be received by said arms and movable along the latter, substantially as set forth.

8. In an apparatus substantially as described, the combination of a double armed 25 catcher having a central depending shaft, a tubular upright receiving said shaft, the shaft and upright having coincident openings, and a pin fitted to said openings whereby it may operate to secure the catcher in different 30 adjustments, substantially as set forth.

9. In an apparatus substantially as described the combination with a crane provided with a ring supporting pin, of a retaining plate adapted to overlie a ring fitted on said 35 plate, and a latch having means engaging with the retaining plate and provided with a head or abutment portion projecting below the ring supporting pin whereby it may lie opposite the ring supported on said pin, substantially as set forth.

EDWARD ROBERTS.
